UNITED STATES PATENT OFFICE.

NELSON K. SMITH, OF DALLAS, TEXAS, ASSIGNOR OF ONE-HALF TO GEORGE W. HOFFMAN, OF HOUSTON, TEXAS.

ROTARY WRENCH CARRIAGE.

Application filed September 30, 1921. Serial No. 504,452.

To all whom it may concern:

Be it known that I, NELSON K. SMITH, a citizen of the United States, residing at Dallas, in the county of Dallas and State of 5 Texas, have invented certain new and useful Improvements in Rotary Wrench Carriages, of which the following is a specification.

This invention relates to new and useful improvements in carriages for supporting 10 pipe wrenches on well drilling rotaries.

It is customary to employ two wrenches in disconnecting the tool joints between sections of well drilling pipe. This invention has to do with a carriage adapted to be 15 mounted on the rotary platform to support the pipe wrench which is engaged with the lower member of the tool joint.

The object of the invention is to provide a carriage which will yieldably support the 20 wrench so as to permit the same to yield downwardly to a certain extent. A further object is to provide a carriage in which the wrench may be easily and readily placed and by which it will be held in proper position. 25 Another feature of the invention is to provide a carriage which may be conveniently handled and placed in position.

One of the objects of the invention is to provide a carriage that is reversible so as to 30 hold the wrench for screwing and unscrewing the sections of tool joints and the like. Another object is to provide means on the carriage for knocking off the upper wrench in case the tubing falls, thus preventing injury to the carriage and protecting the 35 wrench carried thereby.

A construction designed to carry out the invention will be hereinafter described together with other features of the invention.

40 The invention will be more readily understood from a reading of the following specification and by reference to the accompanying drawings, in which an example of the invention is shown and wherein:

45 Fig. 1 is a perspective view of a carriage constructed in accordance with my invention and in position on the platform of a rotary,

Fig. 2 is an elevation of the carriage, portions being in section,

50 Fig. 3 is a plan view of the same, and Fig. 4 is a detail showing the carriage de-

tached.

In the drawings the numeral 10 designates a vertical standard or post which is prefer-

ably cylindrical and has its upper end tele- 50 scoping into a carriage member 11, which has a collar 12 at its lower end. Above the collar the carriage member is slotted so as to lighten it in weight. A laterally offset yoke 13 is formed integral with the member 11 60 and is supported by a pair of curved arms 14 extending to the top of the member and serving as handles to enable the workman to pick up the device and transport it. Curved braces 15 extend downwardly from the yoke 65 and are formed integral with the collar 12. A transverse pin 16 driven into the post 10 within the slotted portion of the member 11 limits the upward displacement of the member and prevents the post from falling out 70 of the member when the same is lifted by the handles 14.

The collar 12 is counter bored at 17 to receive the upper end of a coiled spring 18 which encircles the post. The lower end of 75 the spring is seated in the counter bore 19 of a bottom collar 20 which is suitably fastened on the post. The post projects below the collar 20 so as to enter the usual aperture A in the platform B of an ordinary drilling 80 rig. It will be seen that the member 11 may be depressed, but its downward movement is limited by the engagement of the collar 12 with the collar 20, at which time the spring 18 will be fully compressed. However, the 85 abutting of the two collars prevents crushing of the spring or other injury thereto. The spring has sufficient tension to support the member 11 and if loaded under ordinary 90 conditions, but to yield downwardly when subjected to a greater load or strength.

The yoke 13 is provided with apertures 21, located at each end thereof so as to receive a headed pin 22. The yoke has inclined rear walls 21' diverging from the center. The 95 handle lever 30 of a suitable pipe wrench, such as is illustrated in my co-pending application Ser. No. 504,453 executed on an even date therewith, is inserted in the yoke so as to lie against one of the rear walls 21' 100 thereof, the pin 22 being passed thru an aperture which is provided in said handle lever. Either of the apertures 21 may be used according to the position in which it is desired to hold the wrench. It will be 105 seen that when it is desired to reverse the wrench it is removed from the yoke, turned over and inserted against the other wall and the pin placed in the other aperture.

The carriage is, of course, free to be ro- 110

tated so as to position the jaw 31 in proper relation to the lower section of the tool joint. In applying the wrench the lever 32 is of course, released and the chain 33 5 swung outwardly, so as to be free to be engaged around the tool joint section. It will be seen that the workman has only to release the lever 32 or fasten the same and is not called upon to support the wrench or 10 handle the same. When the chain of the wrench is removed from the tool joint it may be swung back and rested upon the upper end of the member 11. The wrench may be left in the yoke 13 and the whole device 15 bodily removed from the rotary platform when desired. Also by rotating the post 10, the wrench may be swung to one side and out of the way when not in use.

20 If the string of tubing should be dropped the upper wrench (not shown) would either strike upon the arms 14 or upon the upper end of the post 10 which would protrude above the carriage. This would prevent 25 the displacement of the lower wrench from the carriage or joint, as well as saving the same from injury.

What I claim, is:

1. In a rotary well carriage, the combination 30 of a post, a carriage member slidable vertically on the post and resiliently sustained, and means for mounting a pipe wrench on the carriage member.

2. In a rotary well carriage, the combination 35 of a post, a carriage member slidable vertically on the post and resiliently sustained, means for mounting a pipe wrench on the carriage member, and means for limiting the downward movement of the member.

3. A resiliently sustained carriage member 40 capable of yielding downwardly and having a laterally offset portion for receiving and supporting a pipe wrench in position to engage a drill stem.

4. A resiliently sustained carriage member 45 capable of yielding downwardly and having a laterally offset portion for receiving and supporting a pipe wrench in position to engage a drill stem, and means for mounting the wrench on the carriage in a reverse position.

5. In a rotary well carriage, the combination 50 of a post, a stop element on the lower portion of the post, a carriage member slid- 55 able on the post, a handle on the member, means for preventing the post from dropping from the member when the latter is lifted, a wrench receiving element carried 60 by the member, and a coiled spring surrounding the post and supporting the member.

6. In a rotary well carriage, the combination 65 of a post, a carriage member slidable on the post, a handle on the member, means for

70 preventing the post from dropping from the member when the latter is lifted, a wrench receiving element carried by the member, and a coiled spring surrounding the post and supporting the member.

7. In a rotary well carriage, a post, a carriage member mounted to slide vertically on the post, a laterally offset yoke carried by the member for receiving a pipe wrench, 75 means for fastening the wrench in the yoke, and a coiled spring surrounding the post and supporting the carriage member.

8. In a rotary well carriage, a post, a carriage member mounted to slide vertically on the post, a laterally offset yoke carried by the member for receiving a pipe wrench, 80 means for fastening the wrench in the yoke, a coiled spring surrounding the post and supporting the carriage member, and a curved arm extending from the yoke to the body of the member and projecting above 85 the same.

9. In a rotary well carriage, a post, a carriage member mounted to slide vertically on the post, a laterally offset yoke carried by the member for receiving a pipe wrench, 90 means for fastening the wrench in the yoke, and a coiled spring surrounding the post and supporting the carriage member, the yoke having diverging rear walls for sustaining the wrench in reversed positions.

95 10. The combination with a rotary table, of a tong carrying means thereon, and means whereby the tong carrying means may automatically be moved vertically relatively to the table with the movement of pipe tongs with which it is adapted to be connected.

100 11. A tong holding device for rotary drilling machines comprising a vertical member and a tong carrying means vertically movable thereon, said means being arranged to automatically change its vertical position with a vertical movement of the tongs which it is adapted to carry.

105 12. A tong holding device for rotary drilling machines comprising an upright member, a tong carrying means vertically movable thereon, and a spring for yieldingly holding the said tong carrying means in position.

110 13. A tong holding device for rotary drilling machines comprising a post adapted to be supported on the machine, a tong holding member slidable on said post, and a spring for yieldably supporting the tong holding member.

115 14. A tong holding device for rotary drilling machines, comprising a post adapted to be supported on the machine, a bushing on said post, a tong holding member slid- 120 able on said post and a spring between the bushing and tong holding member for yieldably supporting the latter.

125 15. The combination with a rotary drilling machine having a rotary table, of a tong

carrying means carried thereby, tongs engaged by said tong carrying means and adapted to engage a section of pipe to thread it into a coupling upon rotation of the table, 5 and means whereby said tongs and tong carrying means may automatically be moved vertically relatively to the table and rotate therewith whereby the tongs may change their position with the vertical movement 10 of a pipe section when the tongs are in use.

16. The combination with a rotary drilling machine having a rotary table, of a tong carrying means carried thereby, tongs engaged by said tong carrying means and 15 adapted to engage a section of pipe to thread it into a coupling upon rotation of the table, and means whereby said tongs and tong

carrying means may automatically move vertically and horizontally relatively to the table whereby the tongs may change their 20 position with the movement of a pipe section with which the tongs are adapted to engage.

17. In a rotary well carriage, the combination of a post adapted to engage the 25 table of a rotary, a sleeve mounted on the post, a jaw mounted on the sleeve and provided with a transverse slot, and means for fastening a pipe wrench in the slot of the jaw. 30

In testimony whereof I affix my signature.

NELSON K. SMITH.
